ANTENNA

Roger E. Clapp, Cambridge, Mass., assignor, by
mesne assignments, to the United States of
America as represented by the Secretary of
War

Application November 4, 1944, Serial No. 561,932

4 Claims. (Cl. 250—33.65)

1

This invention relates to antennas for producing non-symmetrical radiation patterns and particularly to antennas for producing patterns wherein the intensity of radiated energy varies as a power function of $\csc\theta$ (θ being the angle of radiation with respect to the horizon).

In certain echo detection systems, for example, GCA (ground control of approaching aircraft) apparatus, it is desirable that the energy distribution in one plane throughout a relatively wide angle follow a $\csc^2\theta$ variation. Theoretically this provides a radiation pattern of such character that the echo signals reflected, for instance, from an aircraft coming in at constant altitude will be as strong when the target is distant, say 30 miles, as when it is close in. It also enables the simultaneous viewing of near and distant aircraft in search scanning. Conventional parabolic reflectors do not satisfy these requirements, and moreover it is necessary to tilt the parabolic reflector in order to follow incoming aircraft.

In view of the foregoing, it is a salient object of this invention to afford complete radiation coverage throughout a relatively wide angle in elevation and in conformity with the desired mathematical relation between the intensity of radiated energy and angle of elevation.

A further object is to provide a novel and simple antenna structure comprising a cylindrical parabolic reflector and dipole elements so spaced as to produce a radiation pattern of $\csc^2\theta$ configuration.

In this connection it should be noted that recent investigation has established the possibility that the exact type of pattern desired may be closer to a $\csc^3\theta$ configuration. The present invention has the advantage that it may be readily adapted to cover either case.

These and other novel features and advantages will be apparent from the following disclosure.

In the drawings:

Fig. 1 is a partially diagrammatic view showing the manner in which the antenna may be mounted on a vehicle and the radiation pattern which it produces;

Fig. 2 is a plan view of the antenna; and

Fig. 3 is an elevational view of the antenna; and Fig. 4 shows a preferred embodiment of my invention.

Referring to Figs. 2 and 3, the antenna consists of a dipole array which is fed from a wave guide 7 and which directs its radiated energy against a cylindrical parabolic reflector 5. The spacing and number of the dipole elements 6 along the wave guide 7, in addition to the phasing and

2

energization of each element, and in conjunction with the shape of the reflector 5, determine the shape of the intensity pattern in a vertical plane. The dipoles 6 are mounted on one face of the guide 7 and are energized in a known manner by probes extending into the guide. The cylindrical parabolic reflector 5 concentrates the radiated energy into a rather narrow beam in the horizontal plane. The effective line source of radiation of the dipole array is located near the focal line of the parabolic cylinder, that is, approximately to the nearest half wavelength in air.

Fig. 1 illustrates the device as mounted in a mobile type of search station. The antenna may be used in this instance to produce a PPI (plan position indicator) type of scan whereby the surrounding vicinity is swept periodically with the beam from the antenna. The primary function of such a device is to search for and detect the existence of aircraft in the vicinity, and as such, the pattern desired should vary approximately as $\csc^2\theta$. That is, an airplane flying in from a distance at a constant altitude towards the station should be subjected to and reflect a varying amount of energy to produce constant received signals at the station regardless of the plan position of the aircraft.

The antenna is rotated in azimuth by means which will be described presently. It is apparent that the resolution in azimuth of the system depends upon the beam width of the radiation pattern. Preferably the horizontal beam width should be approximately constant for all values of θ to provide uniform resolution over the field. The cylindrical parabola 5 provides a satisfactory solution to this problem.

To obtain the proper energy distribution in the vertical plane, the spacing of the dipoles 6 may be approximately as follows: Over the length A (Fig. 3) representing approximately two-thirds the length of the array, the dipoles 6 are spaced apart slightly less than a half wavelength. Starting from point P and along the length B, the dipoles 6 are spaced gradually closer together so that at the upper end of the array the spacing is approximately two fifths of a wavelength. This particular spacing has given satisfactory results, although the pattern may be modified if desired by varying the spacing. If, for example, it is determined that the desired radiation pattern is closer to $\csc^3\theta$ rather than $\csc^2\theta$, such variation can be achieved by spacing the dipoles 6 accordingly. It should also be noted that in practice the beam pattern is so adjusted that the peak is elevated slightly above the horizon, as indicated

3

by the line Z in Fig. 1, and the beam cuts off sharply below this line so as to minimize ground interference.

In general, when the dipole spacing is varied, three factors are affected: (1) the sharpness of the beam pattern below the line Z, Fig. 1 is changed; (2) the side lobes are changed; and (3) the vertical coverage of the beam is modified. When the vertical coverage is improved, that is, the curvature of the beam pattern over region X 10 (see Fig. 1) is increased, the sharpness of the beam pattern below the line Z is diminished. Depending upon the relative importance of these factors, the beam may be adjusted to the desired shape. The shape is also governed by the amount of energy radiated from each element 6, which may be adjusted by the depth to which their respective pick-up probes extend into the waveguide 7, Figs. 2 and 3.

The reflector 5 and the waveguide 7 feeding the dipoles 6 are supported vertically in fixed relation to each other on a rotating table 8 provided with gear teeth 12, Figs. 2 and 3. The waveguide 7 is, in this instance, at the center of the table 8, and is coupled through a rotatable joint 9 to the transmitting and receiving means (not shown). A portion of the table 8 is broken away as indicated at Y to more clearly show the waveguide joint. A pinion 10 meshing with the gear 8 is mounted on the shaft of a motor 11 which drives the antenna structure when search scanning is being performed.

The nature of the antenna structure may be such as to require that energy be fed to the top of the dipole array in order that the desired energy distribution will be developed in space. Fig. 4 illustrates this structure. Radio frequency energy is coupled through rotatable joint 9 to waveguide 13 which conducts the energy upwardly to bended section 14. Section 14 routes the energy to the top of waveguide 7 which directs the energy downwardly to the radiating dipoles 6. Moreover, it will be appreciated that the dipole array need not be at the center of rotation so long as the desired spacing between the dipoles and the reflector is maintained.

While I have illustrated and described a selected embodiment of my invention, it is apparent that variations and modifications may be made by those skilled in the art, and therefore I do not desire to limit the scope of the invention to the precise details disclosed herein but wish to avail myself of all improvements and modifications within the purview of the following claims.

I claim:

1. A combined transmitting and receiving antenna for use in radio object-locating apparatus,

comprising a cylindrical parabolic reflector and an array of radiating elements positioned on the focal line of said reflector, said elements being spaced closer together at one end of said array than at the other end thereof and means for controlling the amount of energy radiated from each of said elements to produce a radiation pattern resulting in substantially uniform received signals at said antenna irrespective of the radiation angle of reflecting objects disposed along a substantially horizontal path in the plane of said reflector and radiating elements.

2. An antenna for use in radio object-location comprising a vertically-extending cylindrical parabolic reflector and an array of dipole elements arranged along the focal line of said reflector, said dipole elements being spaced apart by substantially a half wavelength for approximately the lower two-thirds of the length of the array, and being spaced gradually closer together for the upper one-third of the length of the array so as to attain a spacing of substantially two-fifths of a wavelength at the upper end thereof.

25 3. An antenna as claimed in claim 1, wherein said elements are spaced progressively closer together at one end of said array than at the other end thereof.

30 4. An antenna for use in radio object-location comprising a vertically-extending cylindrical parabolic reflector and an array of dipole elements arranged along the focal line of said reflector, said dipole elements being spaced apart by substantially a half wavelength for approximately the lower two-thirds of the length of the array, and being spaced gradually closer together for the upper one-third of the length of the array so as to attain a spacing of substantially two-fifths of a wavelength at the upper end thereof, and means for rotating said reflector and said array in fixed relation to each other.

40 ROGER E. CLAPP.
